COAGULOMETER

Thomas E. Salisbury, Highland Park, Ill., and Michael C. Guerrero, and Edward I. Levy, Miami, Fla., assignors to American Hospital Supply Corporation

Filed Nov. 21, 1974, Ser. No. 525,919

Term of patent 14 years

Int. Cl. D24—01

U.S. Cl. D32—2 C

FIG. 1

FIG. 2

FIG. 3

FIG. 4

FIG. 5

FIG. 6

FIG. 1 is a perspective view of a coagulometer, showing our new design;

FIG. 2 is a front elevational view;

FIG. 3 is a rear elevational view;

FIG. 4 is a top plan view;

FIG. 5 is an end elevation thereof; and

FIG. 6 is an elevation as seen from the side opposite FIG. 5.

We claim:

The ornamental design for a coagulometer, substantially as shown and described.
